BASE FOR LAMPS, STANDS, AND THE LIKE

Irving Fiori, Chicago, Ill., assignor to Art Specialty Co., Chicago, Ill., a corporation of Illinois

Application April 10, 1950, Serial No. 9,089

Term of patent 3½ years

(Cl. D48—20)

To all whom it may concern:

Be it known that I, Irving Fiori, a citizen of the United States, residing at Chicago, in the county of Cook and State of Illinois, have invented a new, original, and ornamental Design for Base for Lamps, Stands, and the like, of which the following is a specification, reference being had to the accompanying drawing, forming a part hereof.

In the drawing—

Fig. 1 is a side perspective view of a base for lamps, stands, and the like;

Fig. 2 is a rear perspective view thereof;
Fig. 3 is a top view thereof; and
Fig. 4 is a front elevational view thereof.
The dominant features of my design are shown in solid lines.

I claim:

The ornamental design for a base for lamps, stands, and the like, as shown and described.

IRVING FIORI.
